US00D809650S

(12) **United States Design Patent** (10) **Patent No.:** **US D809,650 S**
(45) **Date of Patent:** **** Feb. 6, 2018**

(54) **ORAL IRRIGATOR**(71) Applicant: **Water Pik, Inc.**, Fort Collins, CO (US)2,870,932 A 1/1959 Davis
2,984,452 A 5/1961 Hooper
3,089,490 A 5/1963 Goldberg
(Continued)(72) Inventors: **Hyunchul Kim**, Chicago, IL (US);
Scott Thorne, Chicago, IL (US)

FOREIGN PATENT DOCUMENTS

(73) Assignee: **Water Pik, Inc.**, Fort Collins, CO (US)CA 851479 9/1970
CH 655237 4/1986
(Continued)(***) Term: **15 Years**(21) Appl. No.: **29/555,462**(22) Filed: **Feb. 22, 2016**(51) LOC (11) Cl. **24-02**

(52) U.S. Cl.

USPC **D24/111**

FIG. 1 is a front perspective view of an oral irrigator.
FIG. 2 is a front elevation view of the oral irrigator of FIG. 1.FIG. 3 is a rear elevation view of the oral irrigator of FIG. 1.
FIG. 4 is a left side elevation view of the oral irrigator of FIG. 1.FIG. 5 is a right side elevation view of the oral irrigator of FIG. 1.
FIG. 6 is a top plan view of the oral irrigator of FIG. 1; and,

FIG. 7 is a bottom plan view of the oral irrigator of FIG. 1. The broken lines in the drawings illustrate portions of the oral irrigator that form no part of the claimed design.
